that the particular arrangement of counterbalancing means is illustrative only as any other suitable counterbalancing means may be used in lieu thereof.

The individual door sections are connected by hinges 36, best shown in Figs. 3, 4, and 5. Each hinge comprises a pair of sections 36A and 36B preferably formed of sheet metal bent into U-shape and having interengaging portions which we shall now describe in some detail.

Referring particularly to Fig. 4, it will be seen that the hinge section 36A has upstanding sides or ears 38 to which sheet metal cups 40 are welded or otherwise suitably secured. The cups 40 have conically tapered surfaces engaged by the complementary surfaces provided by the sides or upstanding ears 42 of the hinge section 36B, the cups 40 being welded to the sides 38 after the hinge sections 36A and 36B and cups 40 are located in assembled position. The tapered surfaces of the cups 40 and sides 42 form bearings about whose axes the hinge sections pivot.

The cups 40 and sides or ears 38 are provided with elongated openings adapted to receive inserts 44 of metal, plastic or other suitable material. Such inserts have flanges 46 engaging the interior of the cups 40 and are provided with grooves which receive C rings 48 to hold the inserts in the hinges. Each insert has an opening adapted to freely receive the shaft 50 of a track roller.

The inserts 44 are preferably made with two different arrangements of openings for receiving the track roller shafts. In one form of insert this opening is adjacent one end of the insert as indicated in Figs. 3, 5, 8, and 10. In the other form of insert the opening for the track roller shaft is midway of the length of the insert as shown in Fig. 9.

With these two types of inserts, three different positions of the track roller shaft can be provided for any given size of hinge as clearly indicated in Figs. 8, 9, and 10. In Fig. 8 inserts are used with eccentric openings and such openings are positioned to bring the track roller shaft closest to the rear of the door sections. In Fig. 9 inserts are used with central openings, thereby moving the track roller shaft and track roller one step further rearwardly of the door sections. In Fig. 10 the positions of the eccentric opening inserts are reversed over those shown in Fig. 8 to position the track roller two steps rearwardly of the door sections.

In Fig. 11, three different sizes of hinges are shown, the three sizes being identical except that the bearing portions and openings for the inserts are progressively farther rearwardly of the door sections. With these three sizes of hinges and the two types of inserts, nine different roller positions can be obtained. It will be understood of course that the stepped position of the rollers rearwardly of the door sections compensates for the taper of the tracks and permits the entire door to seal simultaneously against the doorjamb when brought into closed position and to break free of such doorjamb immediately upon opening movement of the door.

Where a track roller is to be mounted on the upper portion of the upper door section, only the hinge section 36A need be used, as clearly indicated in Figs. 1 and 2. A similar half hinge could be used to attach the lowermost rollers to the lower door section but in most instances it is preferable to mount these lowermost rollers in ears provided by the plates 34.

In wide doors it has been customary to provide

truss bars of U-shape cross section to increase the rigidity of the door structure. We have found that truss bars of C-shape cross section, as best shown in Figs. 11 and 12, are lighter in weight for the same strength than the U-shaped bars heretofore used. We have also provided a novel and improved arrangement for mounting such C-shape bars on the several door sections.

Referring particularly to Figs. 6 and 7, it will be seen that the C-shaped bars 52 are attached at their ends to the individual door sections by a pair of bolts 54. These bolts 54 have heads which engage one side of a door section and shanks passing through the door section and a special washer 56 (Fig. 14), the shanks being threaded to receive nuts 58. Each washer 56 is of such size as to overlap the edges of a round hole formed in the C-bar 52 and has projecting prongs 60 which grip the wood of which the door sections are formed and prevent relative movement between the C-bar and door section.

Intermediate portions of the C-bars 52 are bent rearwardly of the door sections and are supported on chairs 62. Each chair 62 is of generally U-shape construction, being formed of sheet metal and serving as one section of a hinge being used to replace the section 36A. Each chair section 62 has cups 40 welded thereto in the same manner of which such cups are welded to the hinge section 36A which the chair 62 replaces, it being understood that the chair 62 and the hinge section 36B are pivotally connected in the same manner in which hinge sections 36A and 36B are connected. The chair sections 62 are made with the cups 40 located different distances rearwardly of the door so that such chair sections are useable with the different sizes of hinge sections 36B, indicated in Fig. 11, and such additional sizes as it may be desirable to provide.

The bar receiving end of each side of a chair section 62 is provided with a central recess 64 in which the C-shaped bar 52 is seated. This bar is held in place by a sheet metal cap 66 secured by bolts 68 to laterally projecting ears 70 integral with the sides of chair section 62. The cap 66 has inwardly projecting tongues 72 provided with tapered sides which are wedged into the open side of the C-shaped bar 52 and grip this bar so firmly that the result is the same as though the cap were welded thereto. It will be noted that the cap 66 has a downwardly directed edge 74 overlapping the ears 70 located on one side of the bar 52.

In some instances it is desirable to increase the tension on the truss bars by inserting shims therebeneath. Such a shim is indicated at 76 in Fig. 13 wherein this shim is illustrated as being located between the chair 62 and bar 52. The shim also has lateral extensions 78 located between the ears 70 and adjacent portions of the cover 66.

From the foregoing description taken in connection with the accompanying drawings, it will be seen that we have provided an overhead door of the multisectiion type wherein very simple hinge and combined hinge and truss support members may be readily formed in different sizes to compensate for the taper of the tracks and assure proper sealing of the door when in closed position. Likewise, we have provided an improved truss construction which is simpler, less expensive, and lighter in weight for a given rigidity than the truss constructions of the prior art. Our truss construction incorporates a novel means for securing a rigid load-carrying con-

nection between the truss bar and its supporting chair which requires no drilling of the truss bar and permits the chairs to be quickly affixed to the truss bar and door sections at any positions along the truss bar.

It is to be understood that our invention is not limited to the precise details shown but includes all modifications, variations, and equivalents coming within the scope of the appended claims.

The subject matter disclosed but not claimed herein is claimed in our divisional application, Serial No. 227,901, filed May 23, 1951.

We claim:

1. A hinge for overhead doors of the multisection type comprising a first section formed of sheet metal and having upstanding sides with cups attached thereto, said cups having frusto conical bearing surfaces and said cups and sides having aligned elongated openings, a second hinge section of sheet metal having upstanding sides with frusto conical bearing surfaces engaging the frusto conical bearing surfaces of said cups, inserts located in said elongated openings, said inserts having openings for receiving a roller shaft, and C-rings for holding said inserts in said first-named openings, said inserts being elongated and having their shaft-receiving openings located adjacent one end thereof whereby different positions for said roller shafts can be provided by different arrangements of said inserts in said first-named openings.

2. A hinge for overhead doors of the multisection type comprising a first section formed of sheet metal and having upstanding sides with cups attached thereto, said cups having frusto conical bearing surfaces and said cups and sides having aligned elongated openings, a second hinge section of sheet metal having upstanding sides with frusto conical bearing surfaces engaging the frusto conical bearing surfaces of said cups, inserts located in said elongated openings, said inserts having openings for receiving a roller shaft, said inserts being elongated and having their shaft-receiving openings located adjacent one end thereof whereby different positions for said roller shaft can be provided by different arrangements of said inserts in said first-named openings.

3. A hinge for overhead doors of the multisection type comprising a first section formed of sheet metal and having a substantially flat portion adapted to be secured to a door section and upstanding sides with cups attached thereto, said cups having frusto conical bearing surfaces, a second hinge section of sheet metal having a substantially flat portion adapted to be secured to a door section and upstanding ears with frusto conical bearing surfaces engaging the frusto conical bearing surfaces of said cups, said sections being pivoted about an axis within said cups, said cups and sides having aligned elongated openings, an insert located in each of said elongated openings, said inserts having open-

ings for receiving a roller shaft, said inserts being elongated and having the longitudinal axes thereof disposed substantially perpendicular to the flat portion of said first section and having the shaft-receiving openings located along said longitudinal axes whereby said roller shaft is spaced from the plane of said flat portions of said sections.

4. A hinge for overhead doors of the multisection type comprising a first section formed of sheet metal and having a substantially flat portion adapted to be secured to a door section and upstanding sides with frusto conical bearing surfaces and aligned elongated openings therethrough, a second hinge section of sheet metal having a substantially flat portion adapted to be secured to a door section and upstanding ears with frusto conical bearing surfaces engaging the frusto conical bearing surfaces of said sides, said sections being pivoted about an axis within said elongated openings, an insert located in each of said elongated openings, said inserts having openings for receiving a roller shaft, said inserts being elongated and having the longitudinal axes thereof disposed substantially perpendicular to the flat portion of said first section and having the shaft-receiving openings located along said longitudinal axes whereby said roller shaft is spaced from the plane of said flat portions of said sections.

5. A hinge for overhead doors of the multisection type comprising a first section formed of sheet metal and having upstanding sides with bearing surfaces and aligned openings, a second hinge section of sheet metal having upstanding sides with bearing surfaces engaging the bearing surfaces of said first section, an insert located in each of said openings, said inserts having openings for receiving a roller shaft, said inserts having their shaft-receiving openings so located within the periphery of said inserts that different positions for said roller shaft can be provided by different arrangements of said inserts in said first-named openings.
